UNITED STATES PATENT OFFICE.

EMMIT G. LATTA, OF FRIENDSHIP, NEW YORK, ASSIGNOR OF TWO-THIRDS
TO ADRIAN C. LATTA, OF SAME PLACE, AND HARVEY D. BLAKESLEE,
OF BUFFALO, NEW YORK.

TRACE-CARRIER.

SPECIFICATION forming part of Letters Patent No. 283,260, dated August 14, 1883.

Application filed May 3, 1883. (No model.)

To all whom it may concern:

Be it known that I, EMMIT G. LATTA, of Friendship, in the county of Allegany and State of New York, have invented new and useful Improvements in Trace-Carriers, of which the following is a specification.

This invention relates to an improved trace-carrier which can be applied to the harness after the latter is made up without disarranging the harness, and which can be cheaply cast of malleable iron.

My invention consists of the improvements which will be hereinafter described, and pointed out in the claims.

15 In the accompanying drawings, Figure 1 is a plan view of my improved trace-carrier applied to the harness. Fig. 2 is a detached plan view of the trace-carrier. Fig. 3 is a cross-section in line *x x*, Fig. 1. Fig. 4 is a rear view of the trace-carrier. Fig. 5 is a plan view, showing a modified construction of the trace-carrier.

Like letters of reference refer to like parts in the several figures.

25 A represents the back-strap, B the crupper-strap, and C the hip-straps. D is the ring to which the ends of these straps are secured by sewing.

E is the open frame of the trace-carrier, and 30 F F two hooks projecting rearwardly from the frame E and adapted to support the cockeyes of the traces. As represented in Figs. 1 to 4, the open frame E is composed of cross-bars *f* and side bars, *g*, which together constitute an oblong open frame extending across the ring D. The cross-bars *f* are provided on their under sides with notches or recesses *h*, by which the cross-bars rest upon the ring, and whereby the frame is held on the ring against lateral displacement. The side bars, *g*, are depressed below the cross-bars *f* and the ring D sufficiently to permit the hip-straps C to pass over the side bars, *g*, in their natural position, as represented in Figs. 1 and 3, whereby the frame 40 E is held down upon the ring D. The central

portions of the cross-bars *f* are bent inwardly to clear the ends of the back-strap A and crupper-strap B.

The trace-carrier is applied to the harness by simply drawing the hip-strap C through the open frame E and seating the latter on the ring D, whereby by arranging the hip-straps in their ordinary position the trace-carrier is firmly secured in place. This construction enables the harness-maker to make up the harness without the trace-carrier and to apply a trace-carrier when desired, and it also permits the use of the trace-carrier on old harness which is not made with special reference to the employment of a trace-carrier.

In the modified construction represented in Fig. 5 the frame E extends around the ring D, and is provided with loops *i*, through which the hip-straps pass. When the straps are attached to the ring D in a different form from that shown in the drawings, the side bars or loops of the carrier-frame are adapted to the changed position of the straps.

I claim as my invention—

1. A detachable trace-carrier composed of 70 the frame E, having two hooks, F F, on its lower side, and provided with raised cross-bars *f f*, adapted to pass over the ring D, and depressed side bars, *g g*, adapted to pass under the hip-straps, substantially as set forth. 75

2. The combination, with the ring D and the harness-straps secured thereto, of a detachable trace-carrier composed of a frame, E, and hooks or loops F, substantially as set forth. 80

3. The combination, with the ring D, of a trace-carrier composed of hooks F and an open frame having the cross-bars *f* seated on the ring D, and its end bars, *g*, arranged to pass underneath the hip-straps, substantially as set 85 forth.

EMMIT G. LATTA.
